CLAIM

(57) The ornamental design for a bookmark, as shown and described.

DESCRIPTION

FIG. 1 is a front perspective view of a bookmark showing my new design;

FIG. 2 is a perspective view showing the bookmark as it appears on the page of a book thereof;

FIG. 3 is a top plan view thereof;

FIG. 4 is a bottom plan view thereof;

FIG. 5 is a front view thereof;

FIG. 6 is a rear view thereof; and,

FIG. 7 is a left-side view thereof, the right-side being a mirror image.

The broken lines form no part of the claimed design.
